TAPE-SUPPORTING BRACKET FOR
VENETIAN BLINDSEdward E. Schaefer, Oak Park, Ill., assignor to
Theodore Efron, Chicago, Ill.

Application April 8, 1949, Serial No. 86,292

3 Claims. (Cl. 160—178)

1

This invention relates to an improved Venetian blind structure and more particularly to a novel means for detachably securing slat-supporting tapes to the rails of a Venetian blind.

In the conventional Venetian blind construction, a horizontal upper tilting rail is provided and secured thereto are a plurality of depending slat-supporting tapes, e. g. ladder tapes comprising pairs of parallel tapes connected at regular intervals by cross-linking rungs. The horizontal slats of the blind are supported by the rungs of the ladder tapes, and the tapes are secured at their lower ends to a horizontal bottom rail. A tilting mechanism is provided for tilting the upper rail to open and close the slats of the blind. Operating cords for raising and lowering the blind extend downwardly through openings in the slats and are fastened to the bottom rail.

Venetian blinds, as is well known to housewives and other users thereof, require periodic cleaning and washing, particularly when the blinds are finished in light colors. Although Venetian blinds are available in which the slats are removable for cleaning purposes, no means has ordinarily been provided for readily removing the slat-supporting tapes. In the usual construction, the tapes are more or less permanently secured to the upper and lower rails, for example, by nails, screws, staples, or other fastening means. As a result, it is only with considerable difficulty that the slat-supporting tapes can be removed for cleaning, and the removal procedure involves the danger of tearing the ends of the tapes and the necessity of replacing the nails, screws, staples, or other fastening means when the blind is reassembled. Accordingly, readily detachable slat-supporting tapes are a highly desirable adjunct to the modern Venetian blind thereby permitting soiled tapes to be removed for cleaning or dyeing when it is desired to change the color.

One object of the present invention is to provide a Venetian blind construction in which the slat-supporting tapes may be readily removed and reassembled with ease.

A further object of the invention is to provide a tape-securing bracket for attachment to a rail of a Venetian blind by means of which the slat-supporting tapes may be detachably secured to said rail.

An additional object of the invention is to provide a tape-securing bracket for attachment to the rail of a Venetian blind which is of such construction that it is readily adapted to support the load to which it is subjected without bending or deformation.

2

Still another object of the invention is to provide a tape-securing bracket for attachment to the rail of a Venetian blind which avoids undesirable creases, wrinkles, or bellying in the tapes and effects a smooth, attractive, and unbellied appearance.

Other objects and advantages of the invention will be evident upon reference to the accompanying drawings and the detailed description thereof.

Fig. 1 is a fragmentary front view of the upper portion of a Venetian blind showing a bracket comprising one specific embodiment of my invention as used in conjunction with the upper or tilt rail of the blind;

Fig. 2 is an enlarged top plan view of the bracket taken along the lines 2—2 of Fig. 1;

Fig. 3 is a cross-sectional view taken along the lines 3—3 of Fig. 2;

Fig. 4 is an end view taken along the lines 4—4 of Fig. 2 and showing the bracket in side elevation and the rail in cross-section; and

Fig. 5 is a transverse cross-sectional view taken along the lines 5—5 of Fig. 2.

The particular form of tape-securing bracket depicted in the drawing for purposes of illustration is shown as mounted on the upper or tilt rail of a Venetian blind. However, it will be understood that the bracket may be used with equally satisfactory results on the bottom rail of the blind.

Referring first to Fig. 1, a Venetian blind is shown comprising a head rail 10 having a horizontal tilt rail 11 pivotally supported therebelow with a tilting mechanism 12 of well known construction operatively connected at one end of the rail 11. Mounted on the top surface of the rail 11 adjacent each end thereof is a tape-securing bracket indicated generally at 13. By means hereinafter described in detail, the upper ends of a pair of slat-supporting ladder tapes, each comprising front and rear tape members 14 and 16 (Fig. 4), are detachably secured to the brackets 13. The usual transverse rungs (not shown) extend between each pair of tape members 14 and 16 for supporting the slats 17 of the blind. A pair of cords 18 for raising and lowering the blind extend downwardly from the head rail 10 through openings in the tilt rail 11 and the slats 17 and are secured at their lower ends to a bottom rail (not shown). The upper portions of the cords 18 extend through the head rail 10 and terminate in a downwardly extending loop portion 19 for hand operation in the customary manner.

Referring now to Figs. 2-5, each of the brackets 13 comprises a generally rectangular one-piece body portion or fastening plate 21 provided with a plurality of spaced apertures to permit attachment of the bracket by means of a plurality of screws 22 to the top surface of the rail 11. The body portion 21 of the bracket 13 is also provided with an enlarged aperture in the form of an elongated transverse slot 23 adapted to overlie or register with a corresponding opening in the rail 11 through which the cord 18 extends. In the case of attachment of the bracket 13 to a tilt rail 11, the aperture 23 is necessarily in the form of a transverse slot in order to permit the rail 11 to be tilted without deflecting or binding the cord 18.

Projecting from each side of the body portion 21 at opposite ends thereof is an inwardly extending tab or ear, indicated at 24, 26, 27, and 28, each being laterally spaced from the body portion 21 and integrally connected thereto by means of a plurality of bent connecting portions, indicated at 29, 31, 32, and 33, respectively. As seen particularly in Figs. 3-5, the ears 24, 26, 27, and 28 are thus disposed in an elevated plane spaced from and parallel to the body portion 21. An elongated tape-securing side member or arm in the form of a bar 34 of U-shaped cross-section is pivotally secured at one end to the ear 26 by means of a pin or rivet 36 and is swingable about the pin 36 inwardly of the bracket. If desired, the upper and lower sides of the U-shaped bar 34 may be slightly pinched or crimped toward each other at the free end whereby, when the bar 34 is in closed position, the oppositely disposed ear 24 may be received in tight fitting recessed relation between the sides of the bar 34 for retaining the latter in closed position. A similar tape-securing bar 37 is pivotally attached to the ear 27 by a pin 38 on the opposite side of the bracket 13 and coacts in the same manner with the other ear 28.

The ends of the tape members 14 and 16 are stitched as at 39 to form loops 41, as seen most clearly in Figs. 4 and 5, through which the tape-securing bars 34 and 37 may be inserted for attaching the tapes to the brackets 13. By swinging the free ends of the bars 34 and 37 inwardly of the bracket 13, as shown in dotted lines in Fig. 2, the looped ends 41 of the tape members 14 and 16 can be readily slipped on or removed from the tape-securing bars. When the blind is in assembled condition, the tape members 14 and 16 extend downwardly from the looped ends 41, which are retained by the tape-securing bars 34 and 37, and are deflected to a slight extent outwardly by engagement with the curved or outwardly bowed side edges of the rail 11, as indicated at 42 in Fig. 4 in which the rail 11 is in horizontal or untilted position. From the curved edges 42 the tape members 14 and 16 depend perpendicularly to support the lower portions of the blind structure (not shown).

It will be seen that by this arrangement the weight of the bottom rail and the slats of the blind is supported by the bars 34 and 37 and, furthermore, the weight of the blind and the forces resulting during tilting of the rail 11 urge the bars 34 and 37 outwardly from the bracket into tight engagement with the abutments or retaining ears 24 and 28 whereby to retain the bars in normal, parallel, tape-supporting position. Thus, inadvertent opening of the bars 34 and 37 is completely avoided during normal usage of the assembled blind. When the rail 11 is tilted,

it will be seen that the bars 34 and 37 are urged into closed position to an even greater extent than in the untilted position of the rail 11. The present arrangement, in which the bars 34 and 37 are of U-shaped construction and are firmly retained against outward movement by the ears 24, 26 and 27, 28, permits the bracket to be constructed from relatively thin gauge metal without danger of bending or distortion of the bars 34 and 37 from their normal tape-supporting position.

The spaced relationship of the bars 34 and 37 with respect to the base portion 21 and the top surface of the rail 11 provides the required clearance for readily attaching and detaching the looped ends 41 of the tape members 14 and 16. Obviously, however, the necessary clearance between the tape-engaging arms and the rail could also be obtained by providing appropriate recesses or cut-away portions at the side edges of the rail and mounting the base portion of the bracket so that the bars 34 and 37 project over the recesses. In such an arrangement the bent connecting portions 29, 31, 32, and 33 could be eliminated and the ears 24, 26, 27, and 28 could be substantially coplanar with the base portion 21. Although the use of looped ends on the ladder tapes provides a simple, reliable, and cheap method for attaching the tapes, it is also within the scope of the invention to employ other fastening means for detachably securing the ends of the tape members 14 and 16 to the bars 34 and 37. For example, the ends of the tape members could be provided with a plurality of hooks or bent metal strips for engaging the horizontal bars 34 and 37.

In order to detach the tape members 14 and 16 from the bracket 13, the blind is first lifted at the bottom to remove the weight from the tapes and cord. With the slack produced in the tapes 14 and 16 by lifting of the blind, clearance is thereby provided to permit swinging of the bars 34 and 37 inwardly to open position, as seen in dotted lines in Fig. 2, and the looped ends 41 of the tape members may then be slipped endwise from the free ends of the tape-supporting bars. When the bars 34 and 37 are swung inwardly of the bracket, the end portions of the bar eventually abut or engage the body of the bracket adjacent the bent connecting portions 31 and 32 whereby to limit the pivotal movement of the bars. This is seen clearly in Fig. 2 where the bar 34 is shown in open position in dotted lines with the pivoted end thereof abutting, as at 43, the bracket at the juncture of the portion 31 with the ear 26. By the provision of the same or similar brackets at the bottom rail of the blind and by detaching the cords 18 from the bottom rail, the cords may be withdrawn upwardly and the slats 17 removed endwise from the ladder tapes whereupon the tapes may be completely detached for washing, cleaning, dyeing, or replacement. It will be apparent that to reassemble the blind the foregoing steps are followed in reverse fashion.

The tape-securing bracket comprising the present invention possesses a number of important advantages because the bracket may be formed from relatively light gauge metal with only a few stamping operations employing dies of comparatively simple construction. Moreover, the assembly of the tape-securing arms on the body of the bracket may be accomplished by simple and inexpensive riveting techniques. The provision of pivotally mounted tape-supporting side bars adapted to bear the load imposed upon

the bracket and adapted to be rigidly retained in closed position by the weight of the blind avoids undesirable bending or distortion of the tape-securing arms.

One form of tape-securing bracket which has been used in the past is formed from relatively heavy gauge metal with the tapes extending directly from relatively stiff tape-securing members comprising oppositely extending arms with a spaced portion between the free ends thereof. With this type of bracket the result is an unsightly creased or bellied appearance running throughout a considerable portion of the length of the tapes due to the lack of support at the spaced portions between the arms. By avoiding the use of arms of this character, I eliminate such unattractive and undesired creasing or belllying. By extending the tape members from arms of the type herein disclosed, a smooth flat tape surface is provided on the vertical exposed portions which thus remain free of all undesirable wrinkles and creases during all positions of the blind.

It will also be apparent that the brackets herein described are readily adapted for use with all types of Venetian blinds and are of such simple construction that the tapes and cords may be detached therefrom and re-attached thereto by simple operations requiring neither special tools nor any particular degree of mechanical ability.

Although my invention has been illustrated and described in connection with one particular embodiment thereof, it will be understood that various equivalent structures and modifications of the device may be resorted to without departing from the scope of the invention as defined in the appended claims.

I claim:

1. A bracket for detachably securing the ends of a slat-supporting tape to a rail of a Venetian blind, comprising a one piece body member having a flat central portion adapted to be fastened to a rail, a pair of oppositely disposed ear portions extending toward each other on each side of said body member and adapted to be positioned adjacent the longitudinal edges of the rail, said ear portions being connected to said central portion by means of integral connecting portions bent outwardly from said central portion whereby said ear portions are disposed in a plane parallel to and spaced from said central portion, and a pair of elongated tape-supporting side members in the form of bars having a generally U-shaped cross-section and adapted to have the end portions of a tape detachably secured to the central portions of said bars, each of said bars being pivotally attached at one end thereof to one of said ear portions for swinging movement inwardly of said body member in a plane parallel to said central portion for facilitating attachment and detachment of the ends of the tape, and the opposite free end of each of said bars being adapted upon movement thereof outwardly of said body member to receive the oppositely disposed ear portion within said U-shaped cross-section whereby swinging movement of said bars is restricted within the longitudinal confines of the rail, each of said bars being engageable with the oppositely dis-

posed ear portion solely at the free end of the bar whereby the tape is held in secured attachment on the bracket solely by the central portions of said bars.

- 5 2. A bracket for detachably securing the ends of a slat-supporting tape to a rail of a Venetian blind, comprising a body member having an attaching portion adapted to be secured to the flat lateral surface of a rail, a pair of elongated tape-securing arms swingably attached in spaced relation at opposite sides of said body member and adapted to have the end portions of a tape detachably secured to the central portions of said arms, and stop means provided adjacent the sides of said body member for coaction with said arms to limit the extent of outward swinging movement thereof, said arms each being pivotally attached at one end thereof to said body member and being adapted to swing inwardly from said stop means in a plane parallel to said rail surface for facilitating attachment and detachment of the ends of the tape, and said stop means being operatively engageable with said arms only at the free ends thereof whereby the tape is held in secured attachment on the bracket solely by said central portions of said arms and whereby swinging movement of said arms is restricted within the longitudinal confines of the rail.
- 10 3. A bracket for detachably securing the ends of a slat-supporting tape to a rail of a Venetian blind, comprising a body member having a flat attaching portion adapted to be secured to the flat lateral surface of a rail, a pair of integral connecting portions disposed in spaced relation at opposite sides of said body member and adapted to be positioned adjacent the longitudinal edges of the rail, said connecting portions being bent outwardly from the plane of said attaching portion, and a pair of elongated tape-supporting arms at said opposite sides of said body member each pivotally secured at one end thereof to one of said connecting portions for swinging movement in a plane parallel to said attaching portion and said rail surface, said arms being swingable inwardly of the body member for facilitating attachment and detachment of the ends of the tape to the central portions of the arms, and each of said arms being swingable outwardly into operative engagement at its free end only with the oppositely disposed connecting portion whereby the tape is held in secured attachment on the bracket solely by said central portions of said arms and whereby the oppositely disposed connecting portions provide stop means for restricting swinging movement of the arms within the longitudinal confines of the rail.
